UNITED STATES PATENT OFFICE

126,855

DESIGN FOR AN INFANT'S COLLAPSIBLE STROLLER OR SIMILAR ARTICLE

Leslie Peltier, Delphos, Ohio, assignor to The Delphos Bending Company, Delphos, Ohio, a corporation of Ohio

Application October 2, 1940, Serial No. 95,566

Term of patent 14 years

To all whom it may concern:

Be it known that I, Leslie Peltier, a citizen of the United States, residing at Delphos, in the counties of Allen and Van Wert, State of Ohio, have invented a new, original, and ornamental Design for an Infant's Collapsible Stroller or Similar Article, of which the following is a specification, reference being had to the accompanying drawing, forming a part thereof.

The figure is a perspective view of an infant's collapsible stroller or similar article, showing my new design.

I claim:

The ornamental design for an infant's collapsible stroller or similar article, as shown.

LESLIE PELTIER.
